J. M. BENJAMIN.
WORK POSITIONING DEVICE.
APPLICATION FILED JUNE 3, 1918.

1,400,716.

Patented Dec. 20, 1921.

2 SHEETS—SHEET 2.

UNITED STATES PATENT OFFICE.

JOHN M. BENJAMIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

WORK-POSITIONING DEVICE.

1,400,716.

Specification of Letters Patent. Patented Dec. 20, 1921.

Application filed June 3, 1918. Serial No. 237,918.

To all whom it may concern:

Be it known that I, JOHN M. BENJAMIN, a citizen of the United States, residing at Beverly, in the county of Essex and State 5 of Massachusetts, have invented certain Improvements in Work-Positioning Devices, of which the following description, in connection with the accompanying drawings, is a specification, like reference characters on 10 the drawings indicating like parts in the several figures.

My invention relates to devices for positioning work for the performance upon it of certain operations. The embodiment of 15 the invention here illustrated consists of a band-clamp device employed in heel-attaching machines such as is disclosed in the application of Benjamin F. Mayo, filed June 3, 1918, Serial No. 237,951, in which 20 the nailing operation may be performed in an upward or a downward direction. My improved positioning device is, however, by no means limited in its application to machines of this character.

25 A feature of the invention consists in so organizing the device in a novel manner that it may assume a work-receiving position and a position in which it retains the work for the nailing operation, it being normally 30 held for receiving the work. This normal relation I have shown as obtained by a yieldable member or spring, and in it the arms of the work-engaging band of the illustrated band-clamp are separated to better admit the 35 counter of the shoe operated on, these being forced together to clamp the work as it moves into the operating position against the tension of the spring.

As another feature, the invention provides 40 improved adjusting means. The operating position above mentioned may be controlled, as may the lateral relation of the band, its angle to the horizontal and the separation between its arms.

45 In the accompanyings drawings,

Figure 1 shows a side elevation of one embodiment of my improved positioning device, parts being in section;

Fig. 2 is a horizontal section on the line 50 2-2 of Fig. 1; and

Fig. 3 is a front elevation of the device.

Coöoperating with the machine which is to act upon the work, of which machine there is here shown a nail block 54 supported upon 55 the frame 22 of a heel-attaching apparatus,

as disclosed in the Mayo application previously mentioned, is a clamp or positioning device 388 to receive the rear portion of the shoe operated upon. It is mounted on a slide 390 movable in ways 392 at the front 60 of the standard 22 of the frame. The position of the device is as arranged for upward nailing; but the parts and their relation to one another, save with respect to the inversion of the device as a whole, are 65 identical with those in the machine nailing downwardly. The slide is connected to the usual jack post, which is not herein illustrated, by a sprocket chain 391 extending between a plate 394 secured to the end of the 70 slide and said jack post. The clamping device has a counter-weight 510 joined by a chain 402 to lugs 404 projecting from the rear of the slide 390 near its center. The chain is supported upon a sprocket 406 rotatable at the rear of the ways 392. Extending across the slide 390 are horizontal ways 408 in which is mounted a secondary slide 410, from the front of which project 75 arms 412 curved outwardly and downwardly, 80 and each having a horizontal extension 414. At the forward extremity of each of the arm portions 414 is a sleeve 416 situated horizontally, the axes of the sleeves being in alinement. These sleeves are arranged to 85 turn in the arms and are internally oppositely threaded to receive screws 418, at the inner end of each of which is a vertical carrier arm 420 provided with an inwardly inclined end portion 422. Near the junctions 90 of the portions 420 and 422 is a horizontal way, into which projects a flange 424 upon the work-engaging band 426 of the clamp, this band being of resilient sheet metal. The longitudinally inclined sides of the band 95 are forced by the spring of the metal against anti-friction rolls 428 journaled in the ends 422 of the carrier arms. The band is movable horizontally to bring it into proper transverse relation to the work by a screw 100 430 mounted to turn in a lug 432 on the slide 390, and being threaded into one of the arms 412.

The band is held normally outward in the ways with its ends separated to the maximum extent to receive the work. For this purpose an arm 434, riveted at the center of the rear of the band and extending upwardly and rearwardly, has pivoted to it a lever 436 fulcrumed at 438 upon a bracket 440. This 110

bracket is mounted to move in ways in a vertical extension 442 of the slide 410, and is adjustably held therein by a screw 444 turning in the plate 394 and threaded into the bracket. The lever 436 is of the bell-crank type having an arm provided at its outer end with a horizontal cross extension 446. Below the ends of the extension the bracket has depending arms 448 with bores containing 10 plungers 450 backed by springs 452. These springs force the plungers against the extension 446 of the lever, swinging it about its fulcrum to hold the band at its extreme forward position in the ways of the carrier 15 arm portions 422. The extent to which the work may be moved back in engagement with the clamp is determined by a screw 454 threaded through the lever 436 and contacting with a portion of the slide 410. By adjustment of the screw 454, the point at 20 which the work stops when the jack is swung in may be fixed and its relation to the nail block from the front to the rear of the machine correctly determined. By turning the screw 444, the bracket 440 may be raised and lowered, and this through the lever 436 and arm 434 swings the band about pivots furnished by the sleeves 416. This enables the operator to vary the angle of the band from 25 the horizontal so that it may better coöperate with shoes the heels of which have wedge lifts, so that the heel seat and tread ends are not parallel.

The normal separation between the outer 30 ends of the band may be altered by relative movement of the carriers 420, 422. To effect this, each of the sleeves 416 has at its inner end a pinion 456 connected by an idler 458 fixed on a short spindle journaled in the 35 portion 414 of the clamp arm with a pinion 460 secured to a shaft 462. The shaft 462 is rotatably mounted at the inner ends of both the arm portions 414 and carries a hand wheel 464 by which it may be adjusted. By 40 turning this hand wheel, the sleeves 416 may be rotated by the gearing in either direction. They thus act as nuts to shift the screws 418 longitudinally and with them the carrier arms and the ends of the band supported thereby.

When the jack is in its outer or work receiving position, the clamping device is raised by the chain 391 and weight 510. When the jack post is swung in, the clamping 45 device falls, so that, as the heel seat of the jacked shoe arrives over the nail block, the band 426 is positioned to receive it. The correct normal relation having been determined by adjustment of the screw 444 and 50 the shaft 462, the band is moved along its ways by the engagement of the shoe until the screw 454 is in contact with the slide, at which time the band arms have been forced by the rolls 428 against the counter portion 55 of the shoe to clamp it and the work is prop-

erly alined for the nailing operation. After this has been completed, the swinging out of the jack post raises the clamping device, and, as the shoe leaves the clamp, the band is carried to its normal opened or work receiving 70 position by the pressure of the springs 452.

Having fully described my invention, what I claim as new and desire to secure by Letters Patent of the United States is:

1. In a heeling machine, a work-positioning member having relatively movable arms and being itself movable from a work receiving position to the nailing position, means for moving the member to its receiving position, and means past which the arms travel 80 in the movement of the work-positioning member for controlling their relative movement.

2. In a heeling machine, a work-positioning member movable from an advanced position toward the work rearwardly by contact of said work, guideways for the member, said member and guideways having coöperating projections and depressions, and yieldable means for forcing the positioning member 90 to slide bodily in the guideways toward its advanced position.

3. In a heeling machine, a work-positioning member mounted for movement and having separated arms, and guide means 95 over which the arms move acting in the movement to change the distance between said arms.

4. In a heeling machine, a supporting member, a work-positioning member mounted for movement therein and having separated arms, said supporting member having antifriction devices coöperating with the positioning member in its movement to change the distance between its arms. 100

5. In a heeling machine, a work-positioning member having relatively movable arms and being itself bodily movable from a work receiving position to a position at which the work is retained for operation, and means 110 acting upon the work-positioning member as a whole for normally moving said member to its receiving position with the arms separated to the maximum extent, said arms approaching one another when the positioning member moves toward the operating position.

6. In a heeling machine, a work-positioning member movable from a work receiving position to a position at which the work is retained for operation, means including a lever for normally holding the member in its receiving position, and means coöperating with the lever and constructed and arranged to vary the operating position. 120

7. In a heeling machine, a work-positioning member movable from an advanced position toward the work rearwardly by contact of said work, a lever connected to the member, yieldable means acting upon the le- 130

- ver for forcing the positioning means toward its advanced position, and means contacting with the lever constructed and arranged to vary the extent of rearward movement.
- 5 8. In a heeling machine, a supporting member provided with ways, a flexible work-positioning band movable in the ways, and a spring for moving the band toward the work-receiving position.
- 10 9. In a heeling machine, a supporting member provided with ways, a flexible work-engaging band movable in the ways, a lever connected to the band, and a spring exerting its tension upon the lever.
- 15 10. In a heeling machine, a supporting member provided with ways, a flexible work-positioning band movable in the ways, a spring for moving the band toward the work-receiving position, and an adjustable 70 stop member for limiting the movement of the band.
- 20 11. In a heeling machine, a supporting member provided with ways, a flexible work-engaging band movable in the ways, a lever connected to the band, a spring exerting its tension upon the lever, and a stop screw 75 threaded through the lever.
- 25 12. In a heeling machine, a work-positioning band, a supporting member having an arm extending at each side of the band, a pivoted member mounted in each of the arms and engaging the band, and means connected to the pivoted members and arranged to vary their angular position upon the arms.
- 30 13. In a heeling machine, a work-positioning band, a supporting member having an arm extending at each side of the band, a pivoted member mounted in each of the arms and engaging the band, and connections to 80 the band for varying its angle as permitted by movement of the pivoted members.
- 35 14. In a heeling machine, a work-positioning band, a pivotal mounting for the band, an adjustable member, and connections between the member and the band arranged to vary the angle of said mounting when the member is adjusted.
- 40 15. In a heeling machine, a work-positioning band, a pivotal mounting for the band, a movable member, a screw for moving the member, and connections between the member and the band arranged to effect the pivotal movement of the latter.
- 45 16. In a heeling machine, a work-positioning band, a pivotal mounting for the band, a lever connected to the band, and an adjustable fulcrum member for the lever.
- 50 17. In a heeling machine, a work-positioning band, a pivotal mounting for the band, a lever connected to the band, a movable fulcrum member for the lever, and an adjusting screw threaded through the fulcrum member and contacting with a relatively fixed point.
- 55 18. In a heeling machine, a work-positioning band, a pivotal mounting for the band, a lever connected to the band, an adjustable fulcrum member for the lever, and a spring coöperating with the fulcrum member and lever.
- 60 19. In a heeling machine, a work-positioning band, a pivotal mounting for the band, a lever connected to the band, an adjustable fulcrum member for the lever provided with a recess and a spring seated in the recess and coöperating with the lever.
- 65 20. In a heeling machine, a supporting member, a carrier member having a portion arranged to turn in and move bodily upon the supporting member, operator controlled means arranged to turn the carrier member, and a work-positioning member mounted upon said carrier member.
- 70 21. In a heeling machine, a supporting member, a carrier member having a portion arranged to turn in and move bodily upon the supporting member, a work-positioning member mounted upon the carrier member, connections to the positioning member for turning it with the carrier member, and connections to the carrier member to move it.
- 75 22. In a heeling machine, a supporting member, a carrier member having a portion arranged to turn in and move bodily upon the supporting member, gearing for imparting the bodily movement to the carrier member, and a work-positioning member mounted upon the carrier member.
- 80 23. In a heeling machine, a supporting member, a carrier member having a portion arranged to turn in and move bodily upon the supporting member, a work-positioning member mounted upon the carrier member, and pivotal connections to the positioning member for turning the carrier member.
- 85 24. In a heeling machine, a supporting member, an internally threaded sleeve mounted to turn in the supporting member, a carrier member threaded to engage the sleeve and arranged to turn therein, and a work-positioning member mounted upon the carrier member.
- 90 25. In a heeling machine, a supporting member, an internally threaded sleeve mounted to turn in the supporting member, a carrier member threaded to engage the sleeve, a work-positioning member mounted upon the carrier member, and means arranged to turn the sleeve and thereby move the carrier member.
- 95 26. In a heeling machine, a supporting member, an internally threaded sleeve mounted to turn in the supporting member, a carrier member threaded to engage the sleeve, a pinion fixed to the sleeve, and a shaft journaled in the supporting member and being geared to the pinion.
- 100 27. In a heeling machine, a supporting member, a carrier member having a portion arranged to turn in and move bodily upon the supporting member.

the supporting member, and a work-positioning member mounted to slide upon the carrier member.

28. In a heeling machine, a supporting member, a carrier member having a portion arranged to turn in and move bodily upon the supporting member and being provided with ways, and a work-positioning member movable in the ways.

10 29. In a heeling machine, a frame, a band clamp device including a slide movable vertically upon the frame, there being ways extending transversely of the slide, a secondary slide movable in the ways, a bracket projecting from the secondary slide, carrier members pivoted upon the bracket, a band mounted upon the carrier members, and connections between the band and secondary slide.

15 20 30. In a heeling machine, a frame, a band clamp device including a slide movable vertically upon the frame, there being ways ex-

tending transversely of the slide, a secondary slide movable in the ways, a bracket projecting from the secondary slide, a band 25 mounted to slide upon the bracket, a lever connected to the band, and a fulcrum member for the lever movable from the secondary slide.

31. In a heeling machine, a frame, a band- 30 clamp device including a slide movable vertically upon the frame, there being ways extending transversely of the slide, a secondary slide movable in the ways, a bracket projecting from the secondary slide, carrier 35 members having screw mountings in the bracket, a band mounted upon the carriers, a shaft journaled in the bracket at the rear of the band, a gearing connecting the shaft and screw mountings. 40

In testimony whereof I have signed my name to this specification.

JOHN M. BENJAMIN.
